PRODUCTION OF HIGH OCTANE
PARAFFINIC GASOLINES

Chester C. Crawford, El Cerrito, and Donald L. Fuller and Bernard S. Greensfelder, Oakland, Calif., assignors to Shell Development Company, San Francisco, Calif., a corporation of Delaware

Application November 9, 1942, Serial No. 465,048

6 Claims. (Cl. 196—53)

This invention relates to a process for the production of anti-knock gasoline stocks consisting essentially of paraffinic hydrocarbons.

The object of the invention is to provide a process whereby paraffinic gasoline stocks of better anti-knock qualities may be produced from straight run naphthenic distillates having poor anti-knock properties. A further object of the invention is to provide a process whereby a greater yield of "octane-barrels" may be produced from a given quantity of straight run naphthenic gasoline. A further object of the invention is to provide a process whereby paraffinic gasoline stocks substantially free of aromatic hydrocarbons and having exceptionally high anti-knock characteristics, high lead susceptibility, low bromine number and acid heat number, and which are suitable as preferred base stocks for premium aviation gasoline may be produced by means other than by catalytic cracking.

There is a great demand for gasoline blending stocks suitable for use as base stocks for premium aviation gasoline. In order to avoid deterioration of rubber linings of gasoline tanks and for other reasons such stocks are preferably of relatively non-aromatic character. Also, in order to avoid deterioration in storage, etc., they are preferably substantially free of olefins. In order to meet the requirements they must furthermore have the proper volatility, a high anti-knock characteristic and high lead susceptibility. At present no base stocks having all of these desired characteristics, except those prepared by blending synthetic hydrocarbons, are available although some stocks such as certain fractions of gasoline produced by short cycle catalytic cracking approach the desired properties in most respects.

It is apparent from consideration of the problem that about the only material capable of meeting all of these requirements is a mixture of highly branched paraffin hydrocarbons. With this in mind considerable work has been done in attempts to produce such base stocks from various available distillates. Except for the production of synthetic branched chain paraffin hydrocarbons, for instance by alkylation, these attempts have invariably involved the isomerization of the normal paraffin hydrocarbons from straight run distillates by means of Friedel-

Crafts type isomerization catalysts, such in particular as aluminum chloride. Considerable progress has been made in the isomerization of pure normal paraffin hydrocarbons and some progress has been made in the treatment of straight run gasoline fractions. So far, however, as far as we are aware, it has not been possible to economically produce base stocks of the desired properties by these methods.

There is a great deal of art relating to the catalytic isomerization of hydrocarbons with aluminum chloride catalysts and a number of processes and improvements have been patented. These various processes have generally been developed in the isomerization of pure or relatively pure hydrocarbons such as butane, pentane, hexane, heptane or octane and are primarily adapted for such isomerizations. In the various patents, however, it is generally stated that the processes are also applicable to the isomerization of mixtures of hydrocarbons and various straight run gasolines. While these various processes undoubtedly can be applied for the treatment of certain of such petroleum distillates, they are generally totally unsuited for such use due to the fact that the octane numbers of the majority of straight run petroleum distillates are improved only slightly by such treatment. Thus, it is found that when the majority of straight run distillates of the nature of gasoline are subjected to isomerization treatments known to be effective for the isomerization of pentane, hexane, heptane and the like, the increase in octane number realized is generally only about half of that expected and in many cases is substantially nil. This point is illustrated by the following table wherein there are listed results obtained in the treatment of a variety of typical distillates under isomerization conditions in attempts to improve their octane numbers. The catalyst employed in the several examples was a molten mixture of 7.5% b. w. $AlCl_3$ and 92.5% b. w. $SbCl_3$. The isomerization treatment was in each case effected in the violent mixing of the hydrocarbon and catalyst phases in a turbo mixer. The volume ratio of catalyst phase to hydrocarbon phase was in each case about 0.2:1 and the contact time was in each case 60 minutes. In the first case the temperature was about 100° C. and no hydrogen chloride was added. In all other cases about

2.2% b. w. of hydrogen chloride was added (based on the hydrocarbon) and the temperature was about 80° C. In all cases the conditions employed were capable of giving excellent isomerizations of individual pure hydrocarbons such as n-hexane.

Table I

Material treated	Boiling range	C. F. R. octane No. of feed	C. F. R. octane No. of product	Octane No. raise
Straight run Penn. gasoline.	° C. 15-200	52.5	49.0	-3.5
Straight run Calif. gasoline.	3-136	73	76	+3

Do.	15-150	64	67.5	+3.5
Ventura (Calif.) straight run gasoline.	6-150	68	68	0

It will be appreciated that better results may be obtained with certain distillates. The above results, however, illustrate the relatively poor results generally obtained when it is attempted to produce base stocks of the character described from the majority of typical distillates by the known isomerization methods.

We have now invented an improved process whereby the various distillates such as shown in the above table may be converted in a practical and economical manner to substantially saturated high octane base stocks of the type described.

According to the process of the invention, the material to be treated, preferably a straight run naphthenic gasoline fraction, is first subjected to a specific catalytic hydroforming treatment, non-paraffinic hydrocarbons are extracted, and the remaining material is subjected to a catalytic isomerization treatment, preferably effected as more particularly pointed out below.

The starting material employed in the process of the present invention is a straight run gasoline from naphthenic or mixed base petroleum. Such gasolines invariably consist of a complex mixture of paraffinic hydrocarbons and naphthenic hydrocarbons usually containing minor amounts of olefins and aromatic hydrocarbons. The gasoline fraction employed in the process preferably has a boiling range below about 180° C. Thus, a fraction boiling up to about 180° C. or any more narrowly cut fraction may be suitably employed. A preferred fraction affording a blending stock of superior volatility, for example, has a maximum boiling point of about 95° C.-110° C.

The straight run gasoline, after being fractionated to the desired boiling range, is subjected to a catalytic treatment with a molybdenum oxide catalyst. It is to be specifically pointed out that the beneficial results of the treatment are only obtained with this specific catalytic agent. Other catalytic agents of the same general type such as chromium oxide, titanium oxide, vanadium oxide, iron oxide, nickel oxide, platinum oxide, etc., do not give the desired results. While the process is specific to the use of molybdenum oxide, this catalytic agent may be applied in any of the conventional forms. Thus, it may be used per se, as a mixed gel, or supported upon a suitable carrier or supporting material. The preferred catalyst

comprises molybdenum oxide supported upon an adsorptive alumina. The alumina may be either in the form of alumina alpha monohydrate or gamma alumina, or in the form of one of the stabilized aluminas produced by reacting an adsorptive gamma alumina with a small amount of an oxide of an alkali or alkaline earth metal. The catalyst may also contain relatively small amounts of promoters, if desired. The preferred concentration of molybdenum oxide in the described preferred catalyst is between about 4% and 30% by weight.

The treatment of the molybdenum oxide catalyst is effected under conditions quite similar to those employed in catalytic reforming with this catalyst. The temperature of the treatment may be varied between about 425° C. and 550° C. and is preferably between about 450° C. and 525° C. The pressure may be from atmospheric pressure up to about 60 atmospheres but is preferably between about 2 and 25 atmospheres. The process is preferably effected in the presence of a substantial concentration of recycled hydrogen-rich gas. Suitable partial pressures of hydrogen are, for example, between about 1 and 50 atmospheres. The conditions of temperature, pressure and hydrogen concentration are so adjusted within the above limits that little or no destructive hydrogenation of the gasoline is effected.

During use the catalyst becomes coated with carbonaceous deposits and these are periodically removed by burning in the known manner.

In the above-described treatment with the molybdenum oxide catalyst aromatic hydrocarbons are formed in the gasoline fraction, for instance, by the dehydrogenation of cyclohexane (a hydroaromatic naphthene) and its homologues. These aromatic hydrocarbons are known to be harmful to the subsequent isomerization step and are therefore removed. This may be effected in any of the known manners. For example, the gasoline fraction may be treated with a solvent which selectively removes aromatic hydrocarbons or it may be extractively distilled. Since the removal of aromatic hydrocarbons from petroleum fractions may be effected in a number of efficient ways and these are all well known in the art, this step of the process will not be described in further detail.

The gasoline is then subjected to a catalytic isomerization treatment with a Friedel-Crafts type metal halide isomerization catalyst. The preferred catalysts of this type are aluminum chloride, aluminum bromide and/or zirconium chloride. The catalyst may be employed in any one of several forms. Aluminum chloride, for example, may be employed per se, in the form of a complex of the Gustavson type, or supported upon or mixed with an inert support or filler such as active carbon, active alumina or the like. Any of the known isomerization catalysts of this general type may be employed. Also, catalysts consisting of a liquid melt of a mixture of metal halides comprising free aluminum chloride may be employed. Suitable catalysts of this latter type are described in United States Patents 2,279,291 and 2,279,292.

The isomerization treatment is effected under relatively severe conditions to effect a substantial production of doubly branched paraffin hydrocarbons, for example neohexane (2,2-dimethyl butane). Temperatures ranging from about 50° C. up to about 200° C., depending upon the particular catalyst, are employed. When using a molten salt mixture comprising free aluminum

chloride, the temperature is preferably between about 60° C. and 150° C., and with aluminum chloride complexes of the Gustavson type, the temperature is preferably between about 100° C. and 200° C. The isomerization may be effected at atmospheric pressure but is preferably effected under superatmospheric pressure. Any superatmospheric pressure may be employed. Generally, however, pressures between about 2 and 50 atmospheres are suitable and most practical. The isomerization is effected in the presence of one of the known promoters such as boron fluoride or a hydrogen halide. Generally, the promoter is hydrogen chloride. This may be generated in the isomerization system in a known manner but is usually added directly. The partial pressure of hydrogen chloride may range from traces up to several atmospheres. Preferred partial pressures of hydrogen chloride are from about 1 to about 20 atmospheres. Under these conditions the isomerization is effected in the liquid phase. The isomerization is also preferably effected in the presence of added hydrogen. Preferred partial pressures of hydrogen are, for example, between about 1 and 20 atmospheres. Also, if desired, the isomerization may be effected under a pressure of an added normally gaseous paraffin hydrocarbon in order to allow more drastic isomerization conditions without causing excessive degradation. The contact time is adjusted according to the conditions to avoid excessive degradation, while at the same time affording the desired isomerization. In general, under the relatively drastic conditions described, contact times in the order of 10 to 30 minutes are usually sufficient to attain a maximum improvement in octane number. Somewhat longer or shorter contact times may, however, be sometimes advantageously employed. It is observed that under these conditions a considerable production of doubly branched paraffin hydrocarbons is realized which is not the case when operating under the relatively mild conditions usually employed in the isomerization of pure hydrocarbons such as pentane. The particulars regarding the method of contact of the catalyst and the gasoline, the method of recovering and recycling the hydrogen halide promoter, and the like do not differ from those known in the art and used in the isomerization of pure hydrocarbons, and their detailed description here will not serve any useful purpose.

The above-described combination of process steps constitutes a most advantageous process for the production of blending fuels having the above-described desired characteristics. The octane number rise effected in the above-described isomerization step is much larger than usually obtained when treating ordinary gasoline fractions or gasoline fractions treated under similar conditions with other catalysts. Furthermore, the amount of degradation reactions in the isomerization is low and the life of the isomerization catalysts is appreciably increased. These advantages are due to a much more efficient and clean-cut isomerization treatment producing large amounts of doubly branched hydrocarbons such as neohexane and are, in turn, made possible by the above-described specific treating steps, to which the gasoline fraction is subjected prior to isomerization. While we do not desire to be bound by any theories, it is our belief that the generally unsatisfactory results hitherto obtained in attempts to produce base stocks of the type described by subjecting typical straight run gaso-

lines to known catalytic isomerization processes are due to the composition of the majority of straight run distillates and, more particularly, to the type and concentration of hydrocarbons of naphthenic character. The naphthenic hydrocarbons normally present in appreciable concentrations in such distillates, it is found, play an important role in such isomerization treatments and materially affect the results obtained. One of the unexpected properties of these naphthenic hydrocarbons in such isomerization treatments is their ability in small concentrations to repress the degradation of the paraffin hydrocarbons which normally takes place to a substantial extent. This is illustrated by the following experiments:

Normal hexane containing various concentrations of methyl cyclo-pentane was prepared and subjected to a catalytic isomerization treatment exactly as described above for the examples given in Table I, except that the contact time was in each case 30 minutes and the amount of hydrogen chloride charged was about 4.2%. Since the primary degradation product observed in the degradation of the normally liquid paraffin hydrocarbons is isobutane, the production of this hydrocarbon can be used as a measure of the extent of degradation. The percentages of isobutane found in the products of the isomerization of these hexanes containing various amounts of methyl cyclopentane were as follows:

Table II

Concentration of methyl cyclopentane	Isobutane
Per cent	Per cent
0	12
4.8	8.1
13.2	1.4

In the case of the isomerization of normal pentane at a temperature of 72° C. and contact time of 10 minutes, extensive degradation was totally repressed by the addition of as little as 3.1% of methyl cyclopentane.

It is seen from the above that with respect to the suppression of degradation, the presence of a certain amount of naphthenic hydrocarbons is apparently highly desirable. It is found, however, that naphthenic hydrocarbons exert certain detrimental effects and that for optimum results the concentration of naphthenic hydrocarbons is quite low and, in general, much lower than the concentrations normally present in available petroleum fractions. Thus, it is found that while naphthenic hydrocarbons in concentrations greater than small optimum amounts effectively repress degradation of the paraffin hydrocarbons they materially shorten the active life of the catalyst. This leads to the unexpected finding that the catalyst life is not necessarily dependent upon the amount of degradation as has been hitherto believed. A further detrimental effect of naphthenic hydrocarbons when present in more than small optimum amounts is that they repress to a certain extent the isomerization, particularly the isomerization of branched chain paraffins to the high octane double-branched isomers. This is illustrated by the following experiments:

Normal hexane in admixture with various concentrations of methyl cyclopentane was prepared and subjected to a catalytic isomerization as de-

scribed above for the examples given in Table II. The percentages of the charge converted to neo-hexane (2,2-dimethyl butane) and the percentages of neo-hexane in the hexane fractions were as follows:

Table III

Concentration of methyl cyclopentane	Per cent of charge converted to neo-hexane	Per cent of neo-hexane in the hexane fraction
Per cent	Per cent	Per cent
0%	36	51
4.3%	41	46.5
13.2%	37	44
36%	27	42

The relatively poor increase in octane number obtained when treating stocks containing the usual excessive concentrations of naphthenic hydrocarbons is also partly due to the isomerization of non-hydroaromatic naphthenic hydrocarbons such as methyl cyclopentane, etc., to their hydroaromatic isomers with a consequent depreciation in octane number which partly offsets the increase in octane number effected by the isomerization of the paraffin hydrocarbons. The overall effect of the naphthene concentration upon the increase in octane number obtained is illustrated by the following experiments:

Normal hexane in admixture with various concentrations of methyl cyclopentane was prepared and subjected to a catalytic isomerization as described above for the examples given in Table III. The increases in C. F. R. octane number obtained with the various mixtures were as follows:

Table IV

Concentration of methyl cyclopentane	Increase in C. F. R. octane number
0%	58
4.3%	53
13.2%	46
36%	24

The results tabulated in the above Table II, III and IV are plotted graphically in the attached graph, Figure I, II, III, and IV forming a part of the specification. From these figures the effects of naphthenic hydrocarbons upon the isomerization of hexane are readily apparent. It is believed upon this and other evidence that the effects of this naphthenic hydrocarbon as well as other naphthenic hydrocarbons in the isomerization of petroleum distillates comprising a mixture of such hydrocarbons is analogous.

The ability of the above-described process to produce high octane base stocks of the class described from the typical distillates such as shown in Table I above is, we believe, due largely to the extent of removal of the naphthenic hydrocarbons normally present in such distillates. Molybdenum oxide, it is found, when employed under the above-described hydroforming conditions possesses the unique ability to simultaneously isomerize non-hydroaromatic naphthenic hydrocarbons and convert them to aromatic hydrocarbons. Since under these conditions the isomerized non-hydroaromatic naphthenes are converted to aromatic hydrocarbons, the isomerization reaction is favored with the result that the concentration of naphthenic hydrocar-

bons is reduced to a low and apparently optimum concentration. It is also, of course, possible and probable that other effects of the treatment with a molybdenum oxide catalyst contribute toward the improved results. For example, certain of the paraffin hydrocarbons may undergo mild isomerization which facilitates subsequent treatment with the Friedel-Crafts type metal halide isomerization catalyst.

- 10 While the process of the invention is primarily directed to the production of improved paraffin blending stocks in a more economical manner, it is also to be noted that the process allows the production of a maximum yield of "octane barrels" per given quantity of gasoline treated. Thus, the aromatic hydrocarbons removed after the treatment of the molybdenum oxide catalyst constitute a high octane material suitable for blending in motor fuels or for other uses. Also, 15 if desired, a maximum yield of gasoline having a maximum octane number may be produced by blending the aromatic fraction with the isomerized paraffinic blending stock. The resulting product may not however, have all of the desired properties of the paraffinic blending stock to the production of which the process of the invention is particularly directed but under certain circumstances the use of the aromatic fraction in whole or in part may be warranted.

- 20 We claim as our invention:
1. A process for the production of high octane paraffinic blending stocks suitable for use in aviation gasoline from substantially saturated naphthenic petroleum fractions of gasoline constituents containing non-hydroaromatic naphthenes and paraffins which comprises treating said naphthenic petroleum fraction under hydroforming conditions with a molybdenum oxide catalyst, removing aromatic hydrocarbons from the hydroformate, and treating the substantially aromatic-free remainder with a Friedel-Crafts type isomerization catalyst under isomerization conditions to produce a saturated paraffinic stock of improved octane number.
  2. A process for the production of high octane paraffinic blending stocks suitable for use in aviation gasoline from substantially saturated naphthenic petroleum fractions of gasoline constituents containing non-hydroaromatic naphthenes and paraffins which comprises treating said naphthenic petroleum fraction with a molybdenum oxide catalyst at a temperature between about 425° C. and 550° C., a pressure between about 1 and 60 atmospheres, a partial pressure of hydrogen between about 1 and 50 atmospheres and a liquid hourly space velocity of about 0.1 and 2, removing aromatic hydrocarbons from the thus-treated distillate and treating the substantially aromatic-free distillate with an aluminum chloride isomerization catalyst at a temperature between about 50° C. and 200° C., at a pressure between about 1 and 50 atmospheres, at a contact time between about 10 and 30 minutes under a partial pressure of hydrogen between about 1 and 20 atmospheres, and in the presence of a partial pressure of hydrogen chloride between about 1 and 20 atmospheres to produce a saturated hydrocarbon distillate of improved octane number.
  3. Process according to claim 1 wherein the molybdenum oxide catalyst consists essentially of an activated alumina impregnated with from about 4% to 30% of molybdenum oxide.
  4. Process according to claim 1 wherein the isomerization catalyst consists essentially of a

molten mixture of metal halides comprising free aluminum chloride.

5. Process according to claim 2 wherein the molybdenum catalyst consists essentially of an activated alumina impregnated with from about 4% to 30% of molybdenum oxide.

6. Process according to claim 2 wherein the iso-

merization catalyst consists essentially of a molten mixture of metal halides comprising free aluminum chloride.
